UNITED STATES PATENT OFFICE

JOHN R. GAMMETER, OF AKRON, OHIO, ASSIGNOR TO A. G. SPALDING AND BROS., A CORPORATION OF NEW JERSEY

METHOD OF AND APPARATUS FOR BALL MAKING

Application filed April 26, 1927. Serial No. 186,694.

This invention relates to a method of and apparatus for making a ball having a core held under compression by a tensioned outer structure to provide the high coefficient of elasticity, giving a quick reflexing of the ball, which is an important factor in the long flight of golf balls, for example.

Heretofore the desired stress conditions in golf balls usually have been obtained by winding a rubber thread under high tension upon a core consisting of a flexible envelope containing a fluid or a substance adapted to become fluid before the ball is ready for service, the fluid serving to transmit forces in such manner as to make the elasticity of the tensioned layers of thread the chief factor of resilience.

I have found that it is desirable to wind the thread under such high tension as to exceed the range in which it has a substantially constant coefficient of elasticity and thus to have the thread in the finished ball under such high tension as to function with the increased coefficient of elasticity which comes into play when a rubber thread is stretched almost to its maximum of elongation.

In winding the thread under high tension it has been difficult to regulate the tension of the thread accurately and to avoid breakage of the thread, and the winding of successive layers of the thread has had the effect to some extent of contracting the core and also the first-wound layers of thread and thus of relieving the said first-wound layers of a part of their tension.

In my U. S. Patent No. 1,167,396 a high-tension rubber winding is obtained by winding a liquid-filled core with rubber thread under less than the desired final tension and then expanding the wound structure and thus increasing the tension of the winding by inserting a hollow needle into the core, through the winding, and injecting additional liquid under high pressure into the core, through the needle, but a defect of this practice has been that the needle cuts and weakens the rubber windings.

The chief objects of my invention are to provide a highly stressed ball structure with-

out requiring the winding of rubber thread under such great tension as to be subject to frequent breaking; to provide for increasing the tension of a winding of rubber thread upon a core, after the winding has been done, without cutting or weakening the thread; and to provide without winding rubber thread a ball comprising highly stressed rubber adapted to function with a high coefficient of elasticity to give the ball the desired quick reflexing which is essential to the full elasticity of the ball being expressed against the golf club, for high velocity of the ball, before the ball passes out of contact with the club and, for accuracy, before the ball so changes its relation to the club as to cause the reflexing of the ball to produce a transverse force destroying the accuracy of the shot. A further object is to provide an inexpensive ball having in a high degree the performance characteristics of golf balls of the present standard construction. Another object is to provide in an improved manner a ball comprising a core containing a gas under pressure and thus to employ the high resilience of the gas as a factor of elasticity in the ball as a whole.

Of the accompanying drawings:

Fig. 1 is a side elevation, with parts broken away and parts sectioned, of apparatus embodying and adapted to carry out my invention in its preferred form.

Fig. 2 is a sectional view, with parts in elevation, of a golf ball core and means for injecting a fluid thereinto.

Figs. 3 to 10 are medial sections of inner compression structures suitable for the manufacture of balls in accordance with my invention.

Referring to the drawings, the apparatus comprises a pressure chamber 10 having a fixed end closure 10^a and a removable end closure or door 10^b and provided internally with a pair of rails such as the rail 11 for a series of cars 12, 12 upon each of which is mounted a ball-winding machine 13 which may be of any suitable construction but which preferably is of the general construction shown and described in U. S. Patent No. 1,468,406 to E. L. Schick.

The cars are adapted to abut each other as shown and each winding machine comprises a main drive shaft 14 having at one end a coupling member 15 adapted to mate by simple axial thrust with a coupling member 16 mounted on the adjacent end of the drive shaft of the next adjacent ball-winding machine. An end wall of the tank is traversed by a drive shaft 17 mounted in a packed bearing 18 and provided at its inner end with a coupling member 15 adapted to mate with the coupling member 16 on the end of the next adjacent ball winding machine, the said shaft being provided, outside of the tank, with a belt pulley 19 connected by a belt 20 with a motor 21, for driving the several ball-winding machines while they are in the pressure tank.

For injecting additional pressure fluid into fluid-containing ball cores 22, 22 mounted in the respective machines a hollow needle 23, for each machine, is detachably secured upon the end of the piston-rod 24 of a fluid-pressure cylinder 25 which is supported, in suitable position to insert the needle into a ball core held in the respective winder, by a charging pipe 26 rigidly connecting its rear end with a manifold 27 supported in the pressure chamber and communicating with a supply pipe 28 leading thereinto and provided on the exterior of the chamber with a three-way charging and venting valve 29. For actuating the cylinder's piston in the opposite direction, to withdraw the cylinder from the ball-core, each cylinder is connected at its forward end, by a pipe 30, with a manifold 31, supported in the chamber and communicating with a supply pipe 32 leading into the chamber and provided on the exterior of the chamber with a three-way charging and venting valve 33.

For supplying pressure fluid to each of the hollow needles 23 the rear part of the passage of each needle communicates with a flexible pipe 34 secured to the needle and connected at its other end to a manifold 35 supported in the chamber and communicating with a supply pipe 36 leading into the chamber and provided outside of the chamber with a stop valve 37.

In the preferred practice of my invention a hollow golf ball core having a wall adapted automatically to seal against the escape of pressure fluid therefrom is mounted in each of the winders and the rubber-thread winding is started thereon while the winder is outside of the pressure-chamber. The several winders with the cores therein are then run into the pressure chamber and associated therein as shown and the cylinders 25 are actuated to insert one of the needles 23 into each of the cores.

A fluid under pressure, which may be water or air, is then conducted into the pressure

chamber and at the same time an equal or slightly higher pressure is built up in the cores by forcing an elastic fluid, preferably carbon dioxide or other inert gas, into the cores, the pressures within and upon the exteriors of the cores preferably being kept so nearly balanced as to avoid excessive change in the size of the cores during the winding.

When the pressures have been built up to a suitable magnitude, preferably about 1450 pounds to the square inch, the needles are withdrawn, the winding of the cores is thus effected, the tension of the thread being only such that subsequent expansion of the core, when the external fluid pressure thereon is released, will produce the desired final tension in the winding.

Thus the tension of the thread during the winding may be so comparatively low as to avoid frequent breaking of the thread and other difficulties of winding and tensioning the thread.

If desired, the pressure in the chamber may be gradually reduced as the winding proceeds, and in this way the cores may be caused to remain of almost the same size throughout the winding operation notwithstanding the increasing constricting effect of the winding.

The pressure within the chamber also may be so controlled as to produce only such shrinking of the core under the constricting effect of the winding that upon the final release of the external fluid pressure the inner layers of the winding, partially relaxed by the constriction, will be stretched to substantially the same final condition of tension as the outer layers, notwithstanding the fact that in expanding a laminated hollow structure by internal pressure the inner plies, as a matter of geometry, are given a greater percentage of stretch than the outer plies even though the wall thickness remains the same.

When the cores have been wound to suitable size the machines are stopped, the pressure in the chamber is completely released, the chamber is opened, the winding machines are removed therefrom, the wound cores are removed from the machines and the rubber thread is severed and the end of the winding is anchored by passing it under one or more turns of the winding.

The usual covers, consisting chiefly of gutta percha, are then applied to the wound centers in the usual manner, and the balls are thus completed.

The product is a ball in which the final stretching of the winding, upon the release of the external fluid pressure, brings it to a condition, sometimes called a condition of "super-tension", in which it has so closely approached its limit of elongation as to function with a high coefficient of elasticity in the finished ball, and in which the resistance of the thread to further stretching determines

the final size of the wound core, ready for the cover, with adequate accuracy notwithstanding slight variation in the internal fluid pressure of successive cores.

5 A suitable core for the procedure just described is shown in Fig. 2, the core there shown comprising an inner spherical shell 38 of uncured, non-vulcanizing rubber or rubber compound and an outer spherical shell 10 of vulcanized rubber 39, the unvulcanized rubber being adapted automatically to seal itself against the escape of contained fluid upon the withdrawal of the needle 23. Other self-sealing compounds, such as gelatin or the like, may be employed in place of the raw rubber.

15 As alternatives to employing the core of Fig. 2 and proceeding as above described any one of the cores shown in Figs. 3 to 10 may be employed and put under compression by fluid pressure in the chamber and thus constricted to a suitable size before the winding machines are started, to expand subsequently when the external pressure is released and thus produce the final tensioning of the winding, the employment of the needle being omitted.

20 The core of Fig. 3 comprises a spherical body 40 of vulcanized soft sponge rubber and an imperforate covering of vulcanized rubber 41 thereon adapted to sustain the external fluid pressure to produce a symmetrical compression of the ball.

25 The core of Fig. 4 consists of a sphere of vulcanized sponge rubber having comparatively large cells in its central region and smaller cells near its surface, so that the comparatively dense outer region will maintain the core in spherical form as it is com-

30 pressed by the fluid pressure to smaller size.

The core of Fig. 5 consists of a spherical central portion 42 of sponge rubber and a comparatively thick spherical shell of solid rubber 43 thereon, the thick wall of solid rubber being adapted to develop a high tension strain in the direction of its thickness in the compression of the core.

35 By the use of a suitable blowing agent the sponge rubber core may be so made that the sponge rubber center will be under compression and the solid rubber shell under tension when the core is removed from the vulcanizing mold and before the winding is begun, which permits the core to be reduced to a consider-

40 ably smaller size by external fluid pressure without collapsing or buckling as the result of too small a fluid pressure within the shell as compared with the external fluid pressure.

The core of Fig. 6 comprises a spherical shell 44 of impervious vulcanized rubber containing numerous vulcanized rubber particles, 45, 45, of irregular shape, for which windings of scrap rubber thread may be substituted. A winding of comparatively wide

60 to provide a fluid-tight cover for the scrap rubber of the core.

The core of Fig. 7 is a simple hollow ball of vulcanized rubber, with a thick wall, which is preferably stretched by the use of a blowing agent, by forming it in a body of fluid at super-atmospheric pressure to entrap compressed fluid therein, or by injecting fluid into it, before subjecting it to the external fluid pressure employed in covering it, the stretched condition of the wall permitting it to be compressed to smaller size without buckling.

65 In Fig. 8 is shown a shell of vulcanized rubber formed by molding two hemispherical sections and thereafter cementing or vulcanizing them together, preferably upon a suitable spherical member of vulcanized rubber or other material, each section of the shell being formed with radial recesses extending outward from its inner face, to permit deformation of the rubber under the force of the external fluid pressure.

70 The core of Fig. 9 comprises a pair of hemispherical shells 47, 47 molded of sponge rubber and preferably cemented together and a spherical shell 48 of solid vulcanized rubber enclosing them.

75 The core of Fig. 10 is substantially the same as that of Fig. 9 except that for weighting the ball a central sphere 49 of suitable material, which may be metal or a weighted sphere of raw or vulcanized rubber, is enclosed by the hemispherical shells of sponge rubber.

80 Suitable weighting material may be incorporated in the rubber portion of any of these several types of cores to give the finished ball the desired weight.

85 Various modifications are possible within the scope of my invention as defined in the appended claims.

105 I claim:

1. The method of making a ball which comprises fixing a strain-resisting covering upon a core while holding the core in a body of fluid under super-atmospheric pressure.

110 2. The method of making a ball which comprises forming a core with fluid-containing space therein out of communication with the exterior of the core and fixing a strain-resisting covering upon the core while holding the core in a body of fluid under super-atmospheric pressure.

115 3. The method of making a ball which comprises forming a core with fluid-containing space therein and with a self-sealing wall, injecting fluid into the said space through said wall, permitting said wall to seal itself against a return flow of fluid, and fixing a strain-resisting covering upon the core while holding the core in a body of fluid at super-atmospheric pressure.

120 4. A method as defined in claim 3 in which the fluid is injected into the core while the core is held in a body of fluid which is

14. Apparatus as defined in claim 13 in combination with means in the chamber for injecting fluid into a ball-core contained therein.
15. Ball-making apparatus comprising a pressure chamber and a ball-winding machine therein.
16. Apparatus as defined in claim 15 in combination with means in the chamber for injecting fluid into a ball-core contained therein.
17. Ball-making apparatus comprising a pressure chamber, a ball winder therein, and means in the chamber including a hollow needle mounted for reciprocation for injection of fluid into a ball-core held in the said winder and for withdrawal of the needle from the ball-core.
18. The method of making a ball which comprises winding strand rubber upon a gas-filled core while holding the core in a body of fluid at super-atmospheric pressure.
19. A method of ball making which includes the steps of reducing the size of a compressible element, and thereafter fixing a strain resisting covering thereon.
20. A method of ball making which includes the steps of reducing the size of a compressible element by subjecting it to super-atmospheric external fluid pressure, and thereafter fixing a strain resisting covering thereon.
21. A method of ball making which includes the steps of reducing the size of a compressible object by applying pressure to its entire surface area simultaneously, and thereafter affixing a strain resisting cover thereon.
22. A method of ball making which includes the steps of fixing a strain resisting covering upon a spherical object while holding the object in a body of fluid under super-atmospheric pressure.
23. A method of ball making which includes the steps of winding strand material upon a spherical object while holding said object in a body of fluid under superatmospheric pressure.
24. A method of ball making which includes the steps of forming a compressible spherical object, reducing the size of said object by external pressure thereon, and fixing a cover on said object while it is so held to reduced size.
25. A method of ball making which includes the steps of forming a compressible rubber spherical object, and fixing the rubber of said object in a compressed condition by applying a covering structure thereto while holding the object in a body of fluid at superatmospheric pressure.
- In witness whereof I have hereunto set my hand this 22nd day of April, 1927.
- JOHN R. GAMMETER.

maintained at super-atmospheric pressure throughout injection of fluid into the core and subsequent fixing of the covering material upon the core.

5. The method of making a ball which comprises forming a core with fluid-containing space therein, holding the core in a body of fluid and so increasing the pressure of said fluid and concurrently injecting fluid into said core as to maintain the core's internal and external fluid pressures approximately equal, and fixing a strain-resisting covering upon the core while external fluid pressure is maintained upon the core and without substantial escape of fluid from the core.

10. A method as defined in claim 5 in which the strain-resisting covering is applied to the core by winding strand material thereon.

15. The method of making a ball which comprises winding strand material upon a core while holding the core in a body of fluid at super-atmospheric pressure.

20. The method of making a ball which comprises forming a compressible core, reducing the size of the said core by external pressure thereon, preliminarily to applying a cover thereto, and applying a cover on the core while it is so held to reduced size.

25. The method of making a ball which comprises forming an elastic envelop, distending the same by internal pressure of an elastic fluid, reducing the size of the distended envelop and increasing the pressure of the fluid therein by subjecting it to a preponderating external fluid pressure, and so operating upon the envelop while it is thus held to reduced size as to determine the size it will assume upon release of the external fluid pressure.

30. A method as defined in claim 9 in which fluid is injected into the envelop before it is operated upon as defined to determine its ultimate size.

35. The method of making a ball which comprises forming a rubber core and fixing the rubber of the core in a strained condition by applying a covering structure thereto while holding the core in a body of fluid at super-atmospheric pressure.

40. The method of making a ball which comprises forming a hollow core with a self-sealing wall, injecting fluid into said core through said wall while so increasing the pressure of fluid upon the exterior of the core as to avoid bursting or buckling of the core, and while maintaining the external fluid pressure, permitting said wall to seal itself against a flow of fluid from the core and winding strand material upon the core.

45. Ball-making apparatus comprising a pressure chamber, means in said chamber for applying a covering to a ball-core, and means traversing a wall of the chamber for operating the said applying means while a super-atmospheric fluid pressure is maintained within the chamber.
